METERING VALVE FOR A LAWN SPRINKLER

Mario Anesi, ½ Ansan Tool and Manufacturing Company, Inc., 4750 N. Ronald Ave., Chicago, Ill. 60631

Filed Apr. 11, 1966, Ser. No. 1,838

Term of patent 14 years

(Cl. D91—3)

FIG. 1 is a perspective view of the metering valve for a lawn sprinkler showing my new design;

FIG. 2 is a side elevational view of the metering valve, taken from the blind side of FIG. 1;

FIG. 3 is an end elevational view of the metering valve, taken from the left end of FIG. 2;

FIG. 4 is a top plan view thereof; and

FIG. 5 is a view looking upwardly at the bottom of FIG. 2.

I claim:

The ornamental design for a metering valve for a lawn sprinkler, as shown.
